UNITED STATES PATENT OFFICE

DENIS McDONNELL BROUGHTON, OF LONDON, ENGLAND

RELAY

Application filed November 9, 1929, Serial No. 406,048, and in Great Britain November 9, 1928.

This invention relates to an improved electrical relay with the object of attaining the combination of high sensitivity and ease of adjustment.

5 According to the invention I provide a balanced armature located between and parallel with the arms of a horseshoe magnet and suitably pivoted so that it may oscillate between the poles, to which are attached extension pieces to concentrate the magnetic flux. A coil for controlling the movement of the armature encircles the latter and is located between the arms of the magnet. I further provide a magnetic shunt for controlling the 10 disposition of the magnetic field. This shunt conveniently consists of an adjustable bridge piece of suitable metal making contact with both arms of the magnet. In order to attain the necessary delicacy of adjustment between the armature and its abutting contacts, mechanism is provided whereby movement applied for adjustment purposes is suitably reduced to movement of less extent between the actual contacts. This may be obtained 15 by lever or cam means as will be later described and two forms of contact adjusting mechanism will be described with reference to the drawing.

The mechanism is preferably enclosed in a 20 casing which may take the form of a brass casting, the magnetic shunt being mounted and pivoted in the lid or cover and furnished with an operating and registering pointer on the exterior working in conjunction with a scale. Thus when the cover is in position the bridge piece makes contact with the magnet arms.

This construction provides a strong mechanism of extreme sensitivity and ease of adjustment.

45 It will be appreciated that the magnetic shunt enables the instrument to be adapted to function with exterior circuits of widely differing electrical values, since the bias of the armature to either magnetic pole may be ad-

justed within wide limits and consequently the strength of current necessary to overcome this bias will vary accordingly.

The invention will now be described by way of example only with reference to the accompanying drawing, in which:—

Figure 1 is a diagrammatic plan view of the general assembly of the mechanism.

Figure 2 is a plan view of the lid of the mechanism showing the pointer whereby adjustment is effected and its co-operating scale.

Fig. 3 is a section of one form of adjustable contact device.

Fig. 4 is a section of another form of adjustable contact device.

Referring to Figs. 1 and 2, the permanent magnet A encloses the operating coil T, in the centre of which is the armature F, which is freely pivoted between the magnet poles to which are attached pole extension pieces U1 and U2, the function of which is to concentrate the magnetic flux in the immediate neighbourhood of the end of the armature. The latter is freely pivoted within the coil T. The disposition of the magnetic field is controlled by means of the magnetic shunt B centrally and radially mounted at C and when the cover E is in place serves to adjust the disposition of the field with regard to the poles of the magnet according to its adjustment which is determined and registered by the pointer D on the exterior of the cover E. This provides a simple and very sensitive method of adjustment for the balancing of the armature between its two contacts.

The mechanism is contained within a box casing H and enclosed by the lid E. The screw V holds the magnet rigid within the casing and permits its easy withdrawal when required. The armature weight X serves to balance the armature about its axis Y.

Referring to Fig. 3, delicate adjustment of the armature contacts may be obtained by forming the contact points H half way up a leaf I secured at the bottom and acted upon

by an adjusting screw J with a locking nut K at the top (and free) end. Thus it is obvious that the centre of the leaf spring will only travel half the extent of the travel of the top of the leaf spring and thus adjustment applied to the top of the leaf spring by means of the adjusting screw J will be reduced in extent by half at the point of contact H the proportionate distance of the points of contact and adjustment from the fulcrum L may of course be arranged to meet particular conditions.

A still more delicate arrangement is shown in Fig. 4, in which the sliding contact member M is held against the tapered screw N passing through the passage O in the member M and engaging with the threaded hole P in the base Q by means of the spring R.

Thus adjustment of N will vary the point of contact S upon the taper and minute longitudinal movement of the sliding contact member M will result.

I claim:—

1. A polarized relay comprising a permanent magnet having two arms, a pair of pole pieces secured one to each of said arms, a hollow coil located between said arms, a pair of stationary contacts located adjacent said pole pieces, a pivotally mounted armature extending through said coil and between said pole pieces and said contacts and a magnetic shunt pivotally mounted relatively to said arms, said magnetic shunt being rotatable in a plane parallel to the plane of said magnet, whereby when said shunt is oscillated about its centre it serves simultaneously to increase and decrease the direction and magnitude of the operative field strength through said armature.

2. A polarized relay comprising a permanent magnet having two arms, a pair of pole pieces secured one to each of said arms, a hollow coil located between said arms, a pair of stationary contacts located adjacent said pole pieces, leverage-reducing mechanism for adjusting said contacts, a pivotally-mounted armature extending through said coil and between said pole pieces and said contacts, a balance weight secured to said armature at its end remote from said contacts, a shaft located beyond said coil and between said weight and said contacts, said armature being pivotally mounted on the shaft, and a magnetic shunt being rotatable in a plane parallel to the plane of said magnet.

3. A polarized relay comprising a permanent magnet having two arms, a pair of pole pieces secured one to each of said arms, a hollow coil located between said arms, a pair of stationary contacts located adjacent said pole pieces, leverage-reducing mechanism for adjusting said contacts, said mechanism including a pair of springs secured at one of their ends in a fixed position, said contacts being mounted at about the mid-point of said

springs and adjusting screws bearing against the free ends of said springs, a pivotally-mounted armature extending through said coil and between said pole pieces and said contacts, a balance weight secured to said armature at its end remote from said contacts, a shaft located beyond said coil and between said weight and said contacts, said armature being pivotally mounted on the shaft, and a magnetic shunt pivotally mounted relative to said arms and rotatable in a plane parallel to the plane of said magnet.

In testimony whereof he has signed his name to this specification.

DENIS McDONNELL BROUGHTON.
